UNITED STATES PATENT OFFICE.

ANTONI LYSIAK, OF MANCHESTER, MASSACHUSETTS.

COMPASSES.

1,402,509.

Specification of Letters Patent.

Patented Jan. 3, 1922.

Application filed July 11, 1921. Serial No. 483,782.

To all whom it may concern:

Be it known that I, ANTONI LYSIAK, a citizen of Poland, residing at Manchester, in the county of Essex and State of Massachusetts, 5 have invented certain new and useful Improvements in Compasses, of which the following is a specification.

This invention relates to certain new and useful improvements in compasses and has 10 particular reference to the provision of an improved drafting instrument in the nature of a multiple compass.

The primary object of the invention is to provide a compass of the above kind including more than two adjustably connected marker carrying legs whereby a plurality of circles may be simultaneously made and triangles and rectangles conveniently marked off.

20 Briefly described, the invention consists generally, in a pair of compasses disposed side by side and hingedly connected at their upper ends for swinging toward and away from each other and provided with means 25 for maintaining the same in a desired relation.

With the above general object in view and others that will become apparent as the nature of the invention is better understood, 30 the same consists in the novel form, combination and arrangement of parts hereinafter more fully described, shown in the accompanying drawing and claimed.

In the drawing forming a part of this 35 specification, and in which like characters of reference indicate corresponding parts throughout the several views,

Figure 1 is an edge elevational view of a 40 drafting instrument constructed in accordance with the present invention,

Figure 2 is a side elevational view thereof, and

Figure 3 is a top plan view of the same.

Referring more in detail to the several 45 views, the invention embodies a pair of compasses each including a plate or block 5 with the upper ends of a pair of legs 6 and 7 hinged thereto as at 8 and 9 respectively for swinging movement toward and away from each other, the leg 6 having one end of a curved guide rod 10 fastened therein and slidably extending through an opening in the leg 7 so as to be engaged by a set screw 11 threaded in said leg 7 for maintaining the 50 legs 6 and 7 at any desired position to which they may be swung relative to each other.

The legs 6 and 7 are provided with the usual marker points 12 adjustable longitudinally of said legs and maintained so adjusted by means of a set screw 13. 60

The two pairs of compasses are pivotally connected at their upper ends so as to swing toward and away from each other by means of a leaf hinge 14 having its leaves secured to the adjacent side faces of the plates or 65 blocks 5, and one of the blocks 5 has a curved guide rod 15 fastened thereto, and this guide rod slidably extends through an opening in the other block 5 to be engaged by a set screw 16 threaded therethrough for maintaining 70 said blocks in any adjusted relation. As an additional or equivalent means for adjustably maintaining the proper spaced relation between the two pairs of compasses, the legs 6 and 7 of one pair of compasses may have 75 curved guide rods 17 rigidly fastened thereto and respectively extending through the legs 6 and 7 of the other pair of compasses which are provided with set screws 18 adapted to engage said guide rods 17 for maintaining 80 the desired relation between the two compasses.

In operation, by swinging the two compasses together so that the plates or blocks 5 are in contiguous relation, the device may be 85 employed in the usual way as a single compass and by swinging said compasses in spaced relation as shown in the drawings, one of the points 12 may be used as a pivot so as to scribe three circles or two circles as desired by adjusting the desired remaining points 12 so as to contact with the surface upon which the circles are to be drawn, the various adjustments being obtained in the usual way by loosening and then tightening 90 the various set screws involved in the operation. By varying the relationship between the four legs, and engaging three of the points with the surface, an impression of said points may be made thereon so that 100 when said points are connected by straight lines a triangle will be readily formed of the desired size, and by performing the same operation with respect to all four points, a rectangle of the desired proportions may be 105 readily made. These constitute only a few of the many uses for which the instrument is adapted and which will suggest themselves to one skilled in the art.

From the foregoing description, it is believed that the construction and operation as well as the advantages of the present in- 110

vention will be readily understood and appreciated by those skilled in the art. Minor changes may be made therein without departing from the spirit and scope of the invention as claimed.

What is claimed as new is:

1. As a new drafting instrument, two pairs of compasses each pair comprising a head piece or plate with legs pivoted at their upper ends thereto for swinging toward and away from each other and provided with marking points at their lower ends, said legs being provided with means for retaining the same in any desired adjusted relation, means 10 pivotally connecting said head plates to each other whereby swinging of the pairs of compasses away from or toward each other may be had and the direction of swing of the

pairs relative to each other will be at right angles to the direction of movement of the legs of each pair, and means to adjustably retain the compasses at any desired position to which they may be swung relative to each other.

2. A drafting instrument comprising two pairs of compasses pivotally connected at their upper ends and disposed side by side, and means to retain the compasses in any desired adjusted position to which they may be swung relative to each other, said pairs 25 swinging away from each other in a direction at right angles to the direction of swing of their leg members.

In testimony whereof I affix my signature.

ANTONI LYSIAK.
